DESIGN FOR A DISPLAY PLATE FOR AN AUTOMOBILE

John M. Horn, Chatham Center, N. Y., assignor of one-third to William P. Fagan and one-third to Alfred H. Hurst, both of Albany, N. Y.

Application January 1, 1942, Serial No. 104,966

Term of patent 3½ years

To all whom it may concern:

Be it known that I, John M. Horn, a citizen of the United States, residing at Chatham Center, county of Columbia and State of New York, have invented a new, original, and ornamental Design for a Display Plate for an Automobile, of which the following is a specification, reference being had to the accompanying drawing, forming a part thereof in which—

Fig. 1 is a front elevational view of a display

plate for an automobile showing my new design; and

Fig. 2 is a top view of said plate.

The back of the plate is plain, and the drawing is sectioned to show contrasting colors.

I claim:

The ornamental design for a display plate for an automobile, as shown and described.

JOHN M. HORN.
